UNITED STATES PATENT OFFICE

FRED K. HENDRICKSON, OF WORCESTER, MASSACHUSETTS, ASSIGNOR TO WHITIN MACHINE WORKS, OF WHITINSVILLE, MASSACHUSETTS, A CORPORATION OF MASSACHUSETTS

SPINDLE-STOPPING MECHANISM FOR SPINNING OR TWISTING MACHINES

Application filed November 2, 1929. Serial No. 404,477.

This invention relates to machines in which yarn is spun or twisted. In the operation of such machines, breakage frequently occurs in the spun or twisted thread, or in one of the strands from which the thread is being formed.

It is the general object of my invention to provide improved means for stopping the rotation of a spindle as soon as such breakage occurs in the associated thread or in one of the strands entering into the formation thereof.

A further object is to provide means by which the feed to the strands and the rotation of the spindle are stopped substantially simultaneously.

Another object is to provide a spindle which is driven through a clutch and to provide means for automatically disengaging the clutch upon breakage of yarn or strand. I also provide for applying a braking pressure to the spindle as the clutch is disengaged.

My invention further relates to arrangements and combinations of parts which will be hereinafter described and more particularly pointed out in the appended claims.

A preferred form of the invention is shown in the drawings, in which

Fig. 1 is a sectional side elevation of parts of a twisting machine embodying my improvements;

Fig. 2 is an enlarged sectional side elevation of my improved spindle and clutch mechanism;

Figs. 3, 4 and 5 are sectional plan views, taken along the lines 3—3, 4—4 and 5—5 in Fig. 2 respectively;

Fig. 6 is a view similar to Fig. 2 but showing the parts in a different position; and

Fig. 7 is a sectional view, taken along the line 7—7 in Fig. 6.

Referring to the drawings, I have indicated a portion of the frame 10 of a twisting machine, said frame supporting a spindle

rail 12 on which a plurality of spindles S

are mounted in the usual manner. Strands of yarn Y are drawn from a creel (not shown) and pass under a guide-rod 14, through a guide-wire 15, over a roll 16, around a pressure roll 17 and guide-rod 18, and over an additional roll 19 to a traveler 20 on a ring 22 mounted on a ring-rail 24 which is reciprocated vertically by suitable lifting mechanism, not shown.

The pressure roll 17 is provided with gudgeons or bearing portions 26 rotatable in open bearings 27 at the upper end of a supporting member 28. The member 28 is secured to the upper end of a sliding rod 30 guided vertically in bearings 33 and 34.

A weight W is supported on a belt 36, passing over a guide pulley 37 and connected to a collar 38 clamped on the rod 30. The weight W thus tends to lift the pressure roll 17 out of engagement with the constantly rotated feed rolls 16 and 19.

A latch 40 is pivoted at 41 on the supporting member 28 and engages the under side of a stop plate 42 whenever the latch 40 is moved downward with the member 28. Such engagement retains the member 28 in lowered position, with the roll 17 in free engagement with the feed rolls 16 and 19.

Yarn-controlled mechanism is provided for disengaging the latch 40 and permitting the weight W to raise the pressure roll 17. For this purpose, a slide 50 is mounted in guideways in a stand 51 on the frame 10 and has a portion 52 projecting upward adjacent a rotating shaft 54 on which cams 55 are mounted. Drops 56 are slidably mounted in the portion 52 of the slide 50 and are each provided with a hook-shaped portion at their upper end adapted to engage one of the strands of yarn Y between the guide rod 14 and the guide-wire 15.

Each of these drops 56 is provided with a laterally projecting portion 60 which will be engaged by the cam 55 when the yarn breaks and the drop descends to its lower po-

sition. Such engagement will cause the cam to push the slide 50 outward, so that a projecting portion 62 of the slide will engage the lower end of the latch 40 and free it from the stop plate 42. The weight W is then free to raise the rod 30 and member 28 and thus separate the roll 17 from the feed rolls 16 and 19.

An additional stopping member 65 is mounted on a lever 66 pivoted at 67 on the stand 50 and having an inward extension 68 also supporting a sliding bar in the portion 52 of the slide 50. If the thread T breaks, the member 65 swings upward and the portion 68 thereof moves downward, bringing the corresponding sliding member into position for engagement by the cam 55 and disengaging the latch 40 as previously described.

The details of construction of the stop motion as above described form in themselves no part of my present invention, which relates more particularly to the provision of a clutch device for disengaging and stopping the spindle as the roll 17 is lifted.

Each spindle S is provided with a blade 70, rotatable in an inner sleeve or bolster 71 (Fig. 2). A collar 72 is fixed to the blade 70 and is provided with an upper flange 73 which supports the spool or bobbin B on which the yarn is wound. A driving whirl 75 is mounted on an anti-friction bearing 76, which in turn is supported on the upper portion of the spindle base or casing 77.

A clutch member 80 is axially slidable on the outside of the sleeve 72 and is provided with an annular groove 81 to receive pins 82 in a yoke 83 formed on an arm 84 adjustably secured to the vertically movable rod 30 previously described.

A friction or braking element 85 is secured to the upper side of the yoke 83 in position to engage the under face of the flange 73 as will be hereinafter described.

The upper part of the whirl 75 has a free bearing on a projecting portion 86 of the clutch member 80. This projecting portion 86 is provided with spaced slots 87 (Fig. 5) to receive clutch rollers or balls 88. The lower end portion of the sleeve 72 is provided with flat or cam faces 90 (Fig. 5) providing clearance for the balls 88 when in the mid-position indicated in Fig. 7.

When the parts are positioned as indicated in Fig. 5, the rollers 88 are clutched between the inner surface of the upper part of the whirl 75 and the cam faces 90 of the sleeve 72, thus providing a driving connection between the whirl 75 and the spindle blade 70, the connection being on the order of the well known Horton clutch.

Screws 92 (Fig. 4) are seated in the clutch member 80 and are provided with end portions 93 extending into inclined cam grooves

94 (Fig. 2) in the opposite outer walls of the sleeve 72.

When the clutch member 80 is in the lowered position indicated in Fig. 2, the screw portions 93 and cam grooves 94 cause the member 80 and sleeve 72 to be positioned as indicated in Fig. 5, thus permitting the rollers to lock the whirl 75 to the sleeve 72 and spindle 70.

When the clutch member 80 is raised to the position indicated in Fig. 6, the rollers 88 are moved to the mid-position indicated in Fig. 7, and the whirl 75 rotates freely relative to the blade 70.

Furthermore, as the actuating arm 84 and the clutch member 80 moves upward, the friction member 85 engages the under face of the flange 73, as indicated in Fig. 6, and brings the spindle 70 quickly to rest. A collar 97 on the rod 30 limits upward movement of the rod 30, the spindle blade 70 and the spool B.

A pedal 95 is attached to the lower end of the rod 30 by which the parts may be conveniently re-set after yarn breakage has been repaired. When the rod 30 is moved downward and is latched in running position, as indicated in Fig. 1, the clutch members assume the position indicated in Fig. 2, and the spindle blade 70 is continuously rotated. When the rod 30 is released by the stop motion and moves upward, the arm 84 moves to the position shown in Fig. 6, disconnecting the clutch and applying braking pressure to the flange 73.

I have thus provided simple and effective means for disconnecting and stopping a particular spindle whenever the yarn or thread or any strand thereof associated with said spindle is broken.

While I have indicated certain details of construction of a ball bearing spindle in this application, no claim is made thereto, as this spindle construction forms the subject matter of a separate application, Serial No. 404,478, filed by me Nov. 2, 1929.

Having thus described my invention and the advantages thereof, I do not wish to be limited to the details herein disclosed, otherwise than as set forth in the claim, but what I claim is:—

In a spinning or twisting machine, a spindle comprising a spindle blade, a driving whirl mounted for free rotation concentric therewith and having an internal cylindrical surface spaced from said blade, a sleeve fixed to said blade and having a portion extending within said internal cylindrical surface but spaced therefrom and provided with a plurality of flat external surface portions, rolling members positioned between said flat surface portions and said internal cylindrical surface, a collar slidable on said sleeve and having an end portion extending freely between said internal cylindrical portion of

said whirl and the flattened portion of said sleeve and slotted to receive said rolling members, said sleeve having angularly disposed slots and said collar having studs extending into said slots, and means to move said collar longitudinally on said sleeve, thereby causing relative angular movement between said collar and sleeve effective to release said rolling members from driving engagement with said whirl and sleeve.

In testimony whereof I have hereunto affixed my signature.

FRED K. HENDRICKSON.
